BY MESNE ASSIGNMENTS, TO THE SYMINGTON COMPANY, A CORPORATION OF
MARYLAND.

DRAFT RIGGING.

Application filed March 30, 1922. Serial No. 548,197.

To all whom it may concern:

Be it known that we, BYERS W. KADEL and PERCY R. DRENNING, citizens of the United States, residing at Baltimore city, in the State of Maryland, have invented certain new and useful Improvements in Draft Rigging; and we do hereby declare the following to be a full, clear, and exact description of the invention, such as will enable others skilled in the art to which it appertains to make and use the same.

This invention relates to draft rigging for railway cars and the principal object, generally stated, is to provide a connection between the yoke and coupler, said connection including a vertical key and associated supporting means therefor.

Particularly stated, the invention consists of the provision of supplemental key supporting and guiding members connected to the car frame and provided with rear walls or stops with which latter the rear edge of the vertical coupler key is designed to co-operate in preventing rearward movement 25 of the coupler beyond a predetermined position.

The invention has for a further object the provision of upper and lower supplemental coupler key supporting and guiding members, one of said members being relatively fixed to the draft sills and the other being detachably connected thereto.

A still further object of the invention is to provide a draft rigging including in combination, means for connecting the coupler and yoke so as to permit relative movement therebetween, said connection including a vertical key, means adapted to engage the yoke and prevent rearward movement thereof from normal position, and means for guiding and supporting the said key.

Other objects will be obvious, as hereinafter set forth, reference being had to the accompanying drawings in which:

Figure 1 is a sectional plan view of the center sills and associated parts of a car under-frame showing a draft rigging embodying the invention.

Figure 2 is a central longitudinal vertical sectional view of the construction shown in Figure 1, parts of the mechanism being illustrated in side elevation.

Figure 3 is a transverse vertical sectional

view on the line 3—3 of Figure 2, and viewed in the direction of the arrows.

Figure 4 is a similar view on the line 4—4 of Figure 2, and viewed in the direction of the arrows.

Figure 5 is a sectional plan view on the line 5—5 of Figure 2 with the coupler removed.

Figure 6 is a detail side elevation of a portion of the center sill, illustrating the respective key receiving members of the follower and lower vertical key supporting member riveted to said center sills.

Figure 7 is a detail central longitudinal sectional view through the lower vertical key supporting member.

Referring to the drawings, in which similar reference characters designate corresponding parts in the several views, I have shown among other things the center or draft sills 1 of the car between which is positioned the backstop member or casting 2 connected by rivets 3 to said sills. The bolster 4 and center plate 5 are of ordinary form. Arranged between the coupler 6 and the backstop member 2 is the cushioning means which includes the key connected follower 7 and interposed cushioning mechanism diagrammatically illustrated by the diagonal dot and dash lines in Figure 2.

Cheek plates 8 are riveted to the vertical flanges of the center sills, said cheek plates 25 being provided with bosses 9 adapted to fit within openings formed in the center sills. Slots 10 are formed in said bosses, through which slots passes the key 11 connecting the follower 7. Other usual parts of the draft 90 rigging include the end sill 12 in the form of an angle bar and the cover plate 13 which is preferably riveted to the upper flanges 14 of the center sills 1. A striking casting 15 and associated carry iron 16 are provided, as shown in Figure 2.

Surrounding the cushioning mechanism is a vertically arranged yoke 17 having its forwardly extending yoke arms increased in width, as at 18, to provide an increased bearing area for the vertically arranged coupler connecting key 19. Slots 20 are provided in each yoke arm, the forward portion of the side faces of said slots being inclined or tapered and extending rearwardly into relatively wide portions with parallel opposed

faces, as shown in Figures 1 and 5, thereby providing lateral clearance for the pivotal movement of the coupler key, the key slot in the coupler 6 being adapted to closely 5 embrace the said key.

The vertical coupler key 19 is of a length which provides for its extending above and below the upper and lower faces of the yoke arms, said key being of a length greater 10 than the combined width of the yoke and the coupler 6. The projecting portions of the coupler key are adapted to seat, respectively, in openings formed in the supplemental stop and guide members 21 and 22.

15 The upper supplemental member 21 is in the form of a bridge plate attached by rivets 23 to the top of the upper flanges 14 of the center sills and is provided at its forward end and centrally thereof, with 20 a housing 24, the lower and front walls or ends of which are completely open to form a slot or groove 25 into which the upper projecting portion of the coupler key 19 extends. The groove or slot 25 extends 25 forwardly of the plate and is of a greater width than the coupler key so as to permit of the angling of said key on pivotal movement of the coupler. The side walls and rear wall of the housing 24 project below 30 the plate or body portion of the supplemental member 21, as shown in Figure 2, thereby forming a relatively deep groove or slot in which the upper end of the coupler key is guided, and a rear stop with 35 which the coupler key engages when the cushioning mechanism becomes solid, that is, at the limit of the movement of the cushioning mechanism, the rear edge of the coupler key engages the inner face of the rear wall in said supplemental stop member 21.

The supplemental member 21 is strengthened by a series of webs or flanges, several of which act directly to supplement the 45 strength of the rear wall against which the rear edge of the coupler key abuts. Laterally extending webs or flanges 26 are provided at each end of the plate section and intermediate said webs is another transversely extending web 27 terminating in the rear wall of the housing 24. A centrally located longitudinally arranged web 28 extends between the rear lateral web 26 and the rear wall of said housing, and diagonally 55 extending webs or flanges 29 are arranged between said rear wall and the outer portions of the rear lateral web or flange 26.

The lower supplemental stop member 22 is attached to the center sills beneath the 60 lower flanges thereof by means of a detachable connection which serves to permit the insertion and withdrawal of said supplemental member, thereby allowing the coupler key to be removed and another key 65 inserted. A housing 30 having an open top

and front end is formed on the supplemental member 22, the side, bottom and rear walls of said housing forming a groove or slot 31 into which the lower portion of the coupler key 19 extends. The groove or 70 slot 31 extends forwardly of the supplemental member 22, and is of a greater width than the coupler key so as to permit angling of said key on pivotal movement of the coupler. The rear portion of the groove or 75 slot is relatively narrower and the sides thereof inwardly inclined, as indicated at 32, while the front portion of said groove is of a width equal to the spacing of the side walls of the housing 30. The side walls and 80 rear wall of said housing are relatively high, thereby forming a correspondingly deep groove or slot in which the lower end of the coupler key is guided, and the rear wall with which the coupler key engages 85 when the cushioning mechanism becomes solid; that is, at the limit of the movement of the cushioning mechanism, the rear edge of the coupler key engages the inner face of said rear wall in the supplemental stop member 22. The inner face of the bottom wall of the housing 30 forms a bearing surface for the vertical coupler key. The lower supplemental member 22 is reinforced 90 by means of depending webs or flanges 33 95 extending below the bottom wall of the housing 30 and rearwardly the full length of said member.

The respective rear walls of the upper and lower supplemental stop members 21 100 and 22 are in vertical alignment and this construction, together with their depth, assures equal and maximum distribution of the strains, the rear edges of the coupler key 19 simultaneously engaging said walls 105 when the cushioning mechanism becomes solid. The supplemental members 21 and 22 act to prevent spreading of the yoke arms and they also provide both supporting and guiding means for the coupler key 110 without interfering with the angling thereof.

The lower supplemental member 22 is detachably connected to the center sills by means of a transversely disposed key 34 115 arranged to enter and closely fit within a slot or opening 35 formed in the body portion of the supplemental member 22, said slot being of a shape corresponding to said key. Formed between the slotted portion 120 and rear wall of the housing 30 in said member 22, is a transversely disposed groove 36 adapted to receive the flange 37 of a wear plate 38 interposed between the lower arm of the yoke and said supplemental member. The wear plate 38 is of a width substantially that of the yoke arms and in length equal substantially that of the body portion of the supplemental member 22, said wear plate being preferably posi- 125 130

tioned between shoulder 39 formed by providing a depressed surface into which the wear plate is fitted. The shoulders 39 are formed in the body portion of the supplemental member, said body portion including laterally extending bosses 40. The opening or slot 35 hereinbefore referred to extends through said bosses.

Supporting hangers 41 are arranged adjacent the bosses 40, each of said hangers being formed with a boss 42 having a slot 43 therein corresponding to the shape of and adapted to receive the transverse key 34. A vertically extending flange 44 formed integral with the supporting hangers 41 is connected to the inner face of the center sills by means of rivets 45, the inner opposed ends of said rivets being preferably counter-sunk flush with the inner face of said flange. Horizontally disposed flanges or webs 46 project outwardly from the vertical flange 44 and are connected by rivets 47 to the underface of the lower flanges 48 of the center sills. The hangers 41 form relatively strong supports for the lower supplemental stop member 22, the key 34 being readily insertable and removable through the registering slots in said hangers and supplemental member 22. Cotters 49 serve to retain the key 34, as will be understood.

The yoke 17 is of the vertical type and is supported on a carry iron 50 which is preferably bolted to the car sills 1.

35 We claim:—

1. In a draft rigging, the combination with draft sills of a coupler, a yoke, a vertically arranged key connecting said coupler and yoke, and means provided above and below said key for guiding the same, said means being connected to the draft sills and adapted to prevent the movement of the key in a rearward direction beyond a predetermined position.

45 2. In a draft rigging, the combination with draft sills of a coupler, a yoke, a vertically arranged key connecting said coupler and yoke, and means including upper and lower guide members into which the respective ends of the key extend, said members connected to the draft sills and each having a rear wall adapted to prevent movement of the key in a rearward direction beyond a predetermined position.

55 3. In a draft rigging, the combination with draft sills, of a coupler, a yoke, a vertically arranged key connecting said coupler and yoke, and means carried by said draft sills including upper and lower guide members for said key, each of said members being provided with a rear wall arranged in vertical alinement and adapted to prevent movement of the key in a rearward direction beyond a predetermined position.

65 4. In a draft rigging, the combination

with the center sills, of a coupler, a yoke, a vertically extending key for operatively connecting said coupler and yoke, and means including upper and lower guide members into which the respective ends of said key extend, one of said members being detachably connected to said center sills.

5. In a draft rigging, the combination with the center sills, of a coupler, a yoke, a vertically extending key for operatively connecting said coupler and yoke, and means associated with the respective ends of said key for guiding the same, a portion of said means being detachably connected with said center sills.

6. In a draft rigging, the combination with the draft sills having upper and lower flanges, of a coupler, a yoke, a vertically extending key for operatively connecting said coupler and yoke, and means associated with the respective ends of said key for guiding the same, a portion of said means being detachably connected to the lower flanges of said draft sills.

7. In a draft rigging, the combination with draft sills of a coupler, a yoke, a vertically extending key for operatively connecting said coupler and yoke, and means for guiding the upper end of said key and supporting and guiding the lower end of said key, said means being connected to said draft sills and serving to limit the rearward movement of the key beyond a predetermined position.

8. In a draft rigging, the combination with the center sills, of a coupler, a yoke, a vertically arranged key for operatively connecting said coupler and yoke, and means for supporting and guiding said key, said means including upper and lower members, the latter of which is detachably connected with said center sills.

9. In a draft rigging, the combination with draft sills of a coupler, a yoke, a vertically arranged key for operatively connecting said coupler and yoke, a guide member connected to said draft sills and formed with a housing having an opening in which the upper end of said key is guided, and a supporting member also connected to said draft sills and formed with a housing having an opening in which the lower end of the key is adapted to bear and be supported.

10. In a draft rigging, the combination with draft sills of a coupler, a yoke, a vertically arranged key for operatively connecting said coupler and yoke, a guide member connected to said draft sills and formed with a housing having an opening in which the upper end of said key is guided, and a supporting member also connected to the draft sills and formed with a housing having an opening in which the lower end of the key is adapted to bear and be supported, each of said housings having a rear wall

against which the key abuts for limiting the same after a predetermined rearward movement of said key.

11. In a draft rigging, the combination with spaced draft sills, of a coupler, a yoke, a vertically arranged key for operatively connecting said coupler and yoke, a relatively fixed member connected to said draft sills in which member the upper end of said key is guided, and another member detachably connected to said draft sills, said last mentioned member serving to support and guide the key at its lower end.

12. In a draft rigging, the combination with draft sills, of a coupler, a yoke and cushioning mechanism, means for connecting the yoke and coupler to permit relative movement therebetween, means adapted to engage the yoke to prevent rearward movement of the same from normal position, and means bridging the draft sills for guiding the said means connecting the yoke and coupler.

13. In a draft rigging, the combination with draft sills, of a coupler, a yoke and cushioning mechanism, means connecting the yoke and coupler for permitting relative longitudinal movement, means adapted to engage the yoke at the rear to prevent movement thereof from normal position, and means positioned above and below the draft sills for supporting and guiding said means connecting the yoke and coupler.

14. In a draft rigging, the combination with draft sills, of a coupler, a yoke and cushioning mechanism, means including a vertical key for connecting the yoke and coupler, said means being adapted to permit relative movement between said yoke and coupler, means for restraining rearward movement of said yoke from normal position, and means carried by said draft sills for supporting and guiding said vertical key, a portion of said means being detachably connected to said draft sills.

15. In a draft rigging, the combination with center sills, of a coupler, a yoke and cushioning mechanism, means including a vertical key for connecting the yoke and coupler, said means being adapted to permit relative movement between said yoke and coupler, means engaging the yoke adapted to prevent rearward movement of same from normal position, and means including supplemental stop members carried by the center sills for preventing movement of said key beyond a predetermined position.

16. In a draft rigging, the combination with center sills, of a coupler, a yoke and cushioning mechanism, means including a vertical key for connecting the yoke and coupler, said means being adapted to permit relative movement between said yoke and coupler, means engaging the yoke adapted to prevent rearward movement of the

same from normal position, and means including supplemental members carried by the center sills for guiding said key, each of said members being provided with a rear stop for limiting the rearward movement of said key beyond a predetermined position.

17. In a draft rigging, the combination with center sills, of a coupler, a yoke, a vertically arranged key connecting said coupler and yoke, means including upper and lower members for guiding said key, and means including a key for detachably connecting one of said members to the center sills.

18. In a draft rigging, the combination with center sills, of a coupler, a yoke, a vertically arranged key connecting said coupler and yoke, means including upper and lower members for guiding said key, and means including a rigid hanger connected to said center sills, and a key detachably connecting the lower guide member to said hanger.

19. In a draft rigging, the combination with center sills, of a coupler, a yoke, a vertically arranged key connecting said coupler and yoke, means including upper and lower guide members for said key, and means including spaced hangers connected to said center sills, and a key passing through said hangers and lower guide member for detachably connecting the latter to the center sills.

20. In a draft rigging, the combination with center sills, of a coupler, a yoke, a vertically arranged key connecting said coupler and yoke, means including upper and lower guide members for said key, and a wear plate interposed between the lower guide member and yoke, said wear plate being retained in position by said lower guide member.

21. In a draft rigging, the combination with draft sills, of a coupler, a vertical coupler key, a member for guiding the vertical coupler key, said member involving a bridge plate spanning the draft sills, and a housing formed on said plate having an opening for receiving and guiding said key.

22. In a draft rigging, the combination with center sills, of a coupler, a vertical coupler key, a member for guiding the vertical coupler key, said member involving a bridge plate spanning the center sills, a guide for said key, a wall forming a stop at the end of said guide, and reinforcing webs provided on the bridge plate for said wall.

23. In a draft rigging, the combination with center sills, of a coupler, a vertical coupler key, a member for supporting and guiding the vertical coupler key, said member involving a bridge plate spanning the center sills, and a housing having an open top and open front end, the bottom of said housing forming a bearing surface for said key.

24. In a draft rigging, the combination with draft sills, of a coupler, a vertical coupler key, a member for supporting and guiding the vertical coupler key, said member having a bridge plate spanning the draft sills, a housing forming a guide for said key, and a plurality of longitudinally arranged flanges projecting from the wall of said housing for reinforcing the same.

25. In a draft rigging, the combination with draft sills, of a coupler, a vertical

coupler key, a member for supporting and guiding the coupler key, said member being adapted to span the draft sills and involving a body portion formed with an opening ¹⁵ adapted to receive a retaining key, and guide means in said member, said guide means also serving to support the coupler key.

In testimony whereof we affix our signatures.
